LOUIS G. GOETZ AND TOD EDEBURN, OF CLEVELAND, OHIO, ASSIGNEES TO THE ADAMS-BAGNALL ELECTRIC COMPANY, OF CLEVELAND, OHIO, A CORPORATION OF OHIO.

TIltABLE REFLECTOR FOR HEAD-LAMPS.

1,844,687.

Specification of Letters Patent. Patented June 29, 1920.

Application filed September 20, 1919. Serial No. 227,376.

To all whom it may concern:

Be it known that we, LOUIS G. GOETZ and TOD EDEBURN, both citizens of the United States, residing at Cleveland, in the county of Cuyahoga and State of Ohio, have invented certain new and useful Improvements in Tilttable Reflectors for Head-Lamps, of which the following is a specification.

This invention relates to tilttable reflectors for head lamps, the object of the invention being to provide an improved means for mounting the tilttable reflector in the lamp casing, and means for operating said reflector through the medium of said mounting or supporting means, whereby the reflector may be supported without the use of screws or bolts, and in which the wear of the pivots supporting the reflector will be automatically compensated for and in which the operating means for tilting the reflector may be led from the casing in any direction desired.

In the drawings accompanying and forming part of this specification, Figure 1 is a front view of one form of lamp casing showing in dotted lines the means for supporting the reflector and operating it; Fig. 2 is a vertical cross sectional view thereof.

Similar characters of reference indicate corresponding parts in the several figures of the drawings.

The lamp casing 2 may be of any desired form and construction, and this is also true of the reflector 3, which however is shown of the usual parabolic form. The tilttable reflector is hung by means of a flat formed spring band 4 fastened at the center of the back thereof around the lamp connection 5, which is formed rigid with the rear wall of the reflector. This connection 5 carries the usual bulb not shown.

In the present instance the spring is shown provided with an opening 6 to fit around the lamp socket 5. At diametrically opposite points the lamp casing is provided with a pair of lugs 7, each having a tapered pin 8 adapted to fit into a tapered hole 9 at the end 10 of the spring member 4 and upon which tapered pivots the spring member 4 can be shifted or tilted, the reflector 3 being secured to this spring member 4 by means of the lamp socket 5. By this improved means of supporting the reflector any wear on the pivots is automatically

taken up by the outward pressure of the two arms of the spring 4, and the reflector and its supporting spring is thus supported without the use of any screws or bolts, thus simplifying the construction. The reflector is held in its tilted position by means of a helical spring 11 connected at one end to a hook 12 formed on the reflector and at its opposite end to a hook 13 formed on the lamp casing.

In practice this spring is located at the lower side of the reflector so that the pull thereof always tends to tilt the reflector downward which makes it impossible for a reflector to be in any other than its tilted position should the operating means herein after described break or become loose. For operating the reflector a suitable operating cable or wire 14 is provided, one end of which is connected to the spring member 4 while the opposite end not shown is connected with some suitable operating means located in the vehicle or on the steering post. This operating cable passes through a suitable tubular casing rigidly secured to the lamp casing as at 15 by a suitable coupling 16 and by a suitable operating lever the cable may be operated so that by manipulating it the tilttable reflector may be swung into its normal position against the action of the spring 11. This is usually done by pulling upon the cable, but the same result may be obtained by pushing thereupon in some instances.

From the foregoing it will be observed that the reflector, its lamp socket 5 and its bulb, and the reflector spring supporting member or band 4 are all shiftable as a unit upon the rigid pivots 8 carried by the lamp casing and in consequence the operating wire or cable 14 may be led from the casing in various directions as occasion may require.

In other words, the cable or wire may be guided so that the pull thereon may be in any direction desired with reference to the body of the lamp.

The various details may be more or less changed without departing from the spirit or scope of the present invention.

We claim as our invention:

1. The combination of a lamp casing having a pair of opposed pivots, a tilttable reflector in said casing, and means for shiftable supporting said reflector in its casing and

- comprising spring supporting means extending along a pair of sides of and secured to said reflector and having the forwardly projecting ends thereof mounted upon said pivots.
5. 2. The combination of a lamp casing having a pair of opposed pivots, a tilttable reflector in said casing having a rearwardly extending lamp socket, and means for shiftably supporting said reflector in said lamp casing and comprising a spring member connected to said lamp socket and provided at its forward ends with a pair of openings for the reception of said pivots.
10. 3. The combination of a lamp casing having a pair of opposed pivots, a tilttable reflector having a rearwardly extending lamp socket, and means for shiftably supporting said reflector within said casing and comprising a spring band encircling said lamp socket and having at its forward ends a pair of openings for the reception of said pivots.
15. 4. The combination of a lamp casing having a pair of opposed pivots, a tilttable reflector in said casing, means for shiftably supporting said reflector in its casing and comprising spring supporting means extending along a pair of sides of and secured to said reflector and having the forwardly projecting ends thereof mounted upon said pivots, and means connected with said spring supporting means for shifting it and the reflector as a unitary structure.
20. 5. The combination of a lamp casing having a pair of opposed pivots, a tilttable reflector in said casing having a rearwardly extending lamp socket, means for shiftably supporting said reflector in said lamp casing and comprising a spring member connected to said lamp socket and provided at its forward ends with a pair of openings for the reception of said pivots, and means connected with said spring member for shifting said spring member and reflector as a unitary structure.
25. 46. 6. The combination of a lamp casing having a pair of opposed pivots, a tilttable reflector having a rearwardly extending lamp socket, means for shiftably supporting said reflector within said casing and comprising a spring band encircling said lamp socket and having at its forward ends a pair of openings for the reception of said pivots, and means connected with said spring band for shifting said spring band and reflector as a unitary structure.
30. 55. 7. The combination of a lamp casing having a pair of opposed pivots, a tilttable reflector in said casing, means for shiftably supporting said reflector in its casing and comprising a spring member connected with said reflector adjacent to the apex thereof and having a pair of forwardly projecting ends mounted upon said pivots, a spring connected with said reflector and casing for shifting the reflector in a tilted position, and a wire connected with said spring member and effective to pull the reflector against the connection of said spring into its normal position.
35. 8. The combination of a lamp casing having a pair of opposed pivots, a tilttable reflector in said casing having a rearwardly extending lamp socket, means for shiftably supporting said reflector in said lamp casing and comprising a spring member connected to said lamp socket and provided at its forward ends with a pair of openings for the reception of said pivots, a spring connected with said reflector and casing for maintaining the reflector in a tilted position, and a wire connected with said spring member and effective to pull the reflector against the connection of said spring into its normal position.
40. 9. The combination of a lamp casing having a pair of opposed pivots, a tilttable reflector having a rearwardly extending lamp socket, means for shiftably supporting said reflector within said casing and comprising a spring band encircling said lamp socket and having at its forward ends a pair of openings for the reception of said pivots, a spring connected with said reflector and casing for maintaining the reflector in a tilted position, and a wire connected with said spring band and effective to pull the reflector against the action of said spring into its normal position.
45. 10. The combination of a lamp casing, a tilttable reflector having a rearwardly extending lamp socket, a spring band encircling said lamp socket and having a pair of forwardly projecting ends, interconnecting means between said ends and casing comprising tapered pivots, and openings for the reception of said pivots, a helical spring connected with said reflector and casing for maintaining the reflector in its tilted position, and a casing inclosed cable connected with said spring band for shifting the reflector in a direction opposite to the direction of pull of the spring, the casing of said cable being rigidly connected with the lamp casing.
50. 11. The combination of a lamp casing, a tilttable reflector in said casing, and spring supporting means extending along a pair of sides of said reflector and secured thereto and having forwardly projecting ends, interconnecting means between said ends and casing comprising tapered pivots and openings for the reception of said pivots.
55. 12. The combination of a lamp casing, a tilttable reflector having a rearwardly extending lamp socket, and a spring band encircling said lamp socket, said lamp casing and the forward ends of said spring band having interconnecting means therebetween comprising tapered pivots and openings for the reception of said pivots.

13. The combination of a lamp casing, a tiltable reflector in said casing, a spring member connected with said reflector, said casing and spring member having interconnecting means therebetween comprising tapered pivots and openings for the reception of said pivots, a spring connected with the reflector and casing for holding the reflector in one position, and means connected with 5 said spring member for shifting the reflector.
14. The combination of a lamp casing, a tiltable reflector having a rearwardly extending lamp socket, a spring band 10 interconnecting said lamp socket, said lamp casing and the forward ends of said spring band having interconnecting means therebetween comprising tapered pivots and openings for the reception of said pivots, a spring connected with the reflector and casing for hold- 15
16. The combination of a lamp casing, a tiltable reflector in said casing, means for shiftably supporting said reflector in its casing and comprising a spring member connected with said reflector adjacent to the apex thereof and having a pair of forwardly projecting ends, interconnecting means between said ends and casing comprising tapered pivots and openings for the reception of said pivots, and means for shifting said spring supporting means and the reflector relatively to the casing. 20
17. The combination of a lamp casing, a tiltable reflector having a rearwardly extending lamp socket, a spring band interconnecting said lamp socket, said lamp casing and the forward ends of said spring band having interconnecting means therebetween comprising tapered pivots and openings for the reception of said pivots, a spring connected with the reflector and casing for hold- 25
18. The combination of a lamp casing, a tiltable reflector in said casing, means for shiftably supporting said reflector in its casing and comprising a spring member connected with said reflector adjacent to the apex thereof and having a pair of forwardly projecting ends, interconnecting means between said ends and casing comprising tapered pivots and openings for the reception of said pivots, and means for shifting said spring supporting means and the reflector relatively to the casing. 30
19. The combination of a lamp casing, a tiltable reflector having a rearwardly extending lamp socket, a spring band interconnecting said lamp socket, said lamp casing and the forward ends of said spring band having interconnecting means therebetween comprising tapered pivots and openings for the reception of said pivots, a spring connected with the reflector and casing for hold- 35

ing the reflector in one position, and means connected with said spring band for shifting the reflector.

Signed at Cleveland, county of Cuyahoga, and State of Ohio, this 25th day of September, 1919.

LOUIS G. GOETZ,
TOD EDEBURN.
